CONTAINER DISPENSING SPOUT

Leonard M. Collins, Hollywood, Calif., assignor to Pressure Dispensers, Inc., Hollywood, Calif., a corporation

Application September 13, 1954, Serial No. 32,248

Term of patent 14 years

(Cl. D58—26)

Fig. 1

Fig. 2

Fig. 3

Figure 1 is a front perspective view of a container dispensing spout showing my new design;

I claim:

The ornamental design for a container dispensing spout, substantially as shown.
